UNITED STATES PATENT OFFICE.

LEON WILLIAM EDWARDS, OF FOREST CITY, PENNSYLVANIA.

AUTOMATIC CUT-OFF FOR GAS-BURNERS.

1,254,586.

Specification of Letters Patent. Patented Jan. 22, 1918.

Application filed February 12, 1917. Serial No. 148,152.

To all whom it may concern:

Be it known that I, LEON WILLIAM EDWARDS, a citizen of the United States, residing at Forest City, in the county of Susquehanna and State of Pennsylvania, have invented certain new and useful Improvements in Automatic Cut-Offs for Gas-Burners; and I do declare the following to be a full, clear, and exact description of the invention, such as will enable others skilled in the art to which it appertains to make and use the same.

This invention relates to improvements in attachments for gas burners and similar fixtures.

The principal object of the invention is to provide means for automatically shutting off the flow of gas in case the light is casually blown out or if the flow of gas through the pipes momentarily ceases.

An additional object is to provide a device of this character having a main and supplemental cut-off valve, the latter being normally operated by a thermostat, but which is held in an open position by the opening of the main cut-off valve until the thermostat becomes heated.

With these and many other objects in view, the invention resides in the novel features of construction, combination and arrangement of parts which will be herein-after more particularly described and claimed.

In the accompanying drawings:—
Figure 1 is a side elevation partly in section of a gas burner constructed in accordance with my invention;

Fig. 2 is a detail side elevation of certain of the parts shown in Fig. 1;

Fig. 3 is a front elevation partly in section of the gas burner;

Fig. 4 is a horizontal section on the plane of the line 4—4 of Fig. 1;

Fig. 5 is a view similar to Fig. 4 showing the parts in a slightly different position;

Fig. 6 is a detail perspective view of the thermostat shown in Figs. 1 and 3;

Fig. 7 is a side elevation partly in section of a modified form of burner constructed in accordance with the invention;

Fig. 8 is a horizontal section on the plane of the line 8—8 of Fig. 7; and

Fig. 9 is a detail vertical section on the line 9—9 of Fig. 7.

As shown by the illustrations in the accompanying drawings, my invention may be

embodied in several different forms, all of which, however, operate in substantially the same manner. It is also obvious that each of the burners is provided with a main and a supplemental cut off valve or stop cock, a thermostat for operating the latter, and means operable by the opening of the main stop cock to hold the supplemental valve in an open position until it can be retained in such position by the expansion of the thermostat.

One form of the invention is illustrated in Figs. 1 to 6, this device consisting of a fixture 1 of suitable construction having a horizontal supply pipe 2, one end of which is secured to a source of supply, while the other end is extended upwardly and has a burner 3 fixed thereon. This burner is constructed to receive a gas mantle 4 of any ordinary or preferred design. A stop cock 5 controls the main flow of gas through the supply pipe 2, while a supplemental cut-off valve 6 is positioned in the upright portion 2' immediately below the bottom of the burner 3.

The stop cock 5 is of usual design, it consisting of a casing and a rotatable plug 7, the latter having a key or other form of finger piece 8. The supplemental cut-off valve consists of a casing 9 having a passageway 10 therethrough, a valve seat being provided in said passageway for the reception of a valve 6. The outer end of this valve forms a stem and projects through a stuffing box in the wall of the casing. This outer end of the valve stem is also inclosed in a casing 12 in which is disposed a spring 13 for normally holding the valve closed. An adjusting nut 14 regulates the tension of the spring 13 to vary the resistance against which it is necessary to open the valve, thus regulating the flow of gas therethrough.

Carried by the burner 3 is an upright post or standard 15, the upper end of said post terminating about midway the mantle 4 and having one end of an annular thermostat 16 fixed thereto, said thermostat surrounding the mantle as shown. The other end of the thermostat has a link 17 pivoted thereto, said link connecting said thermostat with a crank 18 formed on the upper end of a vertical rock shaft 19. This shaft 19 is rotatably mounted in suitable bearings carried by the post 15 and extends through the burner to a point adjacent the supplemental cut-off valve 6.

The lower end of the rock shaft carries an arm 20 which is positioned between the cas-

ing 9 and a depending lever 21 which is pivoted within the housing 12 and extends through an opening in the lower side thereof, the intermediate portion of said lever being pivoted to the stem of the valve 6. It will be seen that although the spring 13 normally retains the valve within its seat, yet by movement of the lever 21 in the proper direction, said valve may be opened to allow gas to flow through the passageway 10. The purpose of the arm 20 is to force the lever 21 away from the casing to open said valve. The thermostat 16 is so constructed and the rock shaft 19 and its arm 20 are so connected thereto that when said thermostat is expanded by the heat of the mantle 4, the shaft will be rocked to cause the arm 20 to engage the lever 21 to hold the valve open. As soon as the flame within the mantle 4 is put out through any cause and the thermostat cools, the shaft 19 will be rocked in a direction to disengage the arm 20 from the lever 21 to permit the spring 13 to close said valve.

25 In those burners constructed somewhat similar to the present invention, it is necessary to manually hold the supplemental cut-off valve open until the thermostat is heated sufficiently for it to perform its function, namely, holding the supplemental valve open. In my invention, however, as hereinbefore mentioned, this is accomplished automatically by the opening of the main valve or stop cock 5. One means of carrying out this automatic opening of the supplemental valve is shown in the above mentioned figures and consists of an arm 22 secured to the plug 7 of the stop cock 5 and having a cam-shaped end as at 23, and a sliding rod 24. This rod is suitably disposed to slide on the supply pipe 2 and has one end bent laterally as shown at 25, while the other end is constructed in the form of a loop 26 and surrounds the portion 2' of the supply pipe. The upwardly bent end 25 is adapted to be engaged by the cam face 23 of the arm 22, while the end of the loop 26 engages the lever 21. A spring 27 normally holds the sliding rod 24 out of engagement with the lever 21. With this construction, it will be seen that as soon as the plug 7 is partially rotated to open the stop cock, the cam face 23 will engage the portion 25 of the rod and cause it to be moved in a direction to open the supplemental valve 6. When the thermostat has become thoroughly heated, the stop cock may be opened to its fullest extent, and when in this position, the cam face will not engage the end of said rod 24 so that if the flame is casually extinguished, the supplemental valve may readily close.

An additional means for automatically operating the supplemental cut-off valve when the flame is accidentally extinguished is shown in Figs. 7 to 9. In this case, a

burner 30 having an ordinary tip is illustrated, the gas to said burner being fed through a supply pipe 31 as in the previous form, said gas being controlled by a stop cock 32 and a supplemental cut-off valve 33. In this form, the supplemental cut-off valve is constructed in substantially the same manner as that previously described and illustrated in the first mentioned set of figures. The thermostat 34, however, is somewhat different, it being substantially vertical and composed of one or more strips of metals having different coefficients of expansion.

A bracket 35 extends from the side of the burner over the spring housing 33' of the supplemental valve and has a lever 36 pivoted thereto intermediate its ends as shown at 37. This lever is used to support the thermostat and also to open the supplemental valve. The upper end of the lever carries a laterally extending arm 38 to which the upper end of the thermostat 34 is secured, the lower end of the latter terminating adjacent to the horizontal portion of the bracket 35. The lower end of the lever has a laterally extending arm 39 for engagement with the lever 40 which is connected with the valve stem of the supplemental valve and corresponds to the lever 21 of the first described form.

The thermostat 34 is so constructed that when it is heated by the flame from the tip of the burner, it will bend toward said burner and thus cause the lever 36 to rock on its pivot 37, thereby moving the lower end of said lever in a direction to open the supplemental valve. As soon as the flame is extinguished, however, the thermostat cools and assumes its vertical or straight position and causes the lever to rock in such a direction as to close the valve and cut off the flow of gas.

The means for holding the supplemental cut-off valve open until the thermostat becomes thoroughly heated may be constructed as shown in Figs. 1 to 6 or as shown in Figs. 7 to 9. That shown in the last mentioned series of figures is used when the supply pipe of the burner is short, or when it is otherwise desirable to have the stop cock 32 disposed adjacent the upright part of the supply pipe or beneath the housing 33'. In such a case the upper end of the plug 32' of the stop cock 32 is provided with a laterally extending arm having an upwardly bent portion 41, said end being adapted to engage the end of the lever 40 when the plug is rotated to partially open said stop cock. When this engagement between the end of the lever 40 and the end 41 of the arm takes place, the valve of the supplemental cut-off valve will be forced open against the tension of its spring, but as soon as the thermostat becomes heated and the stop cock 32 is opened to its fullest extent, the two parts will be

disengaged so that the supplemental valve will be free to close as soon as the thermostat cools.

Thus it will be seen that this arm with its upwardly bent end 41 serves the same purpose as the rod 24 of the first described form. It will also be obvious that it may be used with the annular thermostat as well as the straight thermostat shown in Fig. 7.

Having thus described my invention, what I claim is:—

1. In a device of the class described, the combination with a supply pipe, a burner on the end thereof, a cut-off valve in said pipe, a contractile spring for normally retaining said valve closed, an upright post carried by the burner, an annular thermostat surrounding said burner and having one end attached to the end of the post, a link pivoted to the other end of the thermostat, an upright rock shaft having a crank on its upper end connected with said link, and an arm on the lower end of the shaft for engagement with said cut-off valve to hold the same open against the tension of said spring when the thermostat is heated.

2. In a device of the class described, the combination with a supply pipe, a burner on the end thereof, a cut-off valve in said pipe, a spring for normally retaining said valve closed, an upright post carried by the burner, a thermostat adjacent said burner and having one end attached to the post, a link pivoted to the other end of the thermo-

stat, an upright shaft having its upper end connected with said link, and an arm on the lower end of the shaft for engagement with said cut-off valve to hold the same open against the tension of said spring when the thermostat is heated.

3. In a device of the class described, the combination with a supply pipe, a plug cock therein, a burner on the end of the pipe, a supplemental cut-off valve in the supply pipe, said valve being normally closed, a thermostat for holding said supplemental valve open when the same is heated, said valve being closed when the thermostat is cool, a rod slideable horizontally on said supply pipe and spaced therefrom and having one end in engagement with said cut-off valve, a spring for holding said rod in an operative position, and a cam carried on the upper end of the stem of said cock, said cam engaging the other end of said rod to hold said supplemental valve open against the tension of said spring until the thermostat becomes heated and said cam being operated by the rotation of said plug to open said cock.

In testimony whereof I have hereunto set my hand in the presence of two subscribing witnesses.

LEON WILLIAM EDWARDS.
